CLAIM

The ornamental design for a light switch, as shown and described.

DESCRIPTION

FIG. 1 is a perspective view of a light switch; FIG. 2 is a top plan view of the light switch of FIG. 1; FIG. 3 is a bottom plan view of the light switch of FIG. 1; FIG. 4 is a right side view of the light switch of FIG. 1; FIG. 5 is a left side view of the light switch of FIG. 1; FIG. 6 is a front view of the light switch of FIG. 1; and, FIG. 7 is a rear view of the light switch of FIG. 1. The broken lines in the drawings depict portions of the light switch that form no part of the claimed design.
